United States Patent Office

Des. 225,391
Patented Dec. 12, 1972

225,391

CONE CAP

Alberto Birlain Schaffler, Amsterdam 218-201,
Mexico City, Mexico

Filed Jan. 14, 1971, Ser. No. 106,638

Term of patent 14 years

Int. Cl. D2—03

U.S. Cl. D2—250

FIG. 1

FIG. 2

FIG. 1 is a front elevational view of a cone cap showing my new design; and

FIG. 2 is a top plan view thereof in blank form.

I claim:

The ornamental design for a cone cap, as shown.
